UNITED STATES PATENT OFFICE.

HARRY S. AUSTIN, OF ROME, NEW YORK.

COMBINATION SEAT AND TABLE.

1,271,830.

Specification of Letters Patent.

Patented July 9, 1918.

Application filed May 4, 1917, Serial No. 166,424. Renewed June 6, 1918. Serial No. 238,622.

To all whom it may concern:

Be it known that I, HARRY S. AUSTIN, a citizen of the United States, residing at Rome, in the county of Oneida and State of New York, have invented certain new and useful Improvements in Combination Seats and Tables; and I do hereby declare the following to be a full, clear, and exact description of the invention, such as will enable others skilled in the art to which it appertains to make and use the same.

This invention relates to a combined seat and table and has for one of its objects the provision of a device of this character, whereby the same may be readily converted into a table or a seat when desired.

Another object of this invention is the provision of a pair of relatively spaced end members having a board pivotally connected thereto, which is adapted to be swung into a horizontal position to form a table, and which may be readily swung to a substantially vertical position to form a back rest for the seat.

A further object of this invention is the provision of means for locking the board in a substantially horizontal position and upon the end members to form a table, which will prevent it from becoming accidentally converted from a table into a seat.

A further object of this invention is the provision of a novel means for pivotally connecting the board to the side members whereby the board may be swung into a vertical position upon either side of the end members for the purpose of making a seat, which will be accessible from either side thereof, when desired. A still further object of this invention is the provision of a combination seat and table of the above stated character, which shall be simple, durable and efficient, and which may be manufactured and sold at a comparatively low cost.

With these and other objects in view, as will become more apparent as the description proceeds, the invention consists of certain novel features of construction, combination and arrangement of parts as will be hereinafter more fully described and claimed.

For a complete understanding of my invention, reference is to be had to the following description and accompanying drawings, in which:

Figure 1 is a perspective view of a seat

constructed in accordance with my invention,

Fig. 2 is an end elevation of a table constructed in accordance with my invention,

Fig. 3 is a front elevation of a seat, 60

Fig. 4 is a transverse sectional view of the seat,

Fig. 5 is a detail sectional view illustrating the means for pivotally connecting the board to the side members, 65

Fig. 6 is a detail elevation illustrating arms for connecting the board to the side members,

Fig. 7 is a detail sectional view of a modified means for connecting the arms to the 70 side members.

Referring in detail to the drawings, the numeral 1 indicates substantially U-shaped end members which have their web portions 2 disposed uppermost to form arm rests. 75 Transversely extending members 3 connect the arm portions of the substantially U-shaped members together and have their ends turned downwardly to form supporting feet 4. The members 3 are connected by 80 a longitudinally extending reinforcing strip 6. Vertical reinforcing members 7 are secured to the members 3 and to the web portions 2 of the substantially U-shaped members 1 and have secured thereto, plates 8, 85

which are provided with circular grooves 9 having communicating therewith downwardly depending grooves 10. A substantially rectangular board 11 has secured thereto adjacent each end, reinforcing strips 90 12, on which are formed arms 13 that are provided with elongated slots 14. Bolts 15 extend through the elongated slots 14 and the vertical reinforcing members 7 whereby the arms 13 are pivotally and slidably connected to the end members 1. Formed upon the free ends of the arms 13 are pins 16, which extend into the circular grooves 9 and adapted to travel in the downwardly depending grooves 10 when the device is converted into a table, and which will be hereinafter more fully described. 95

A rack 17 is secured to the substantially U-shaped members in any well known manner and has secured thereto by hinges 18, a 100 cover 19, which will form a seat to the device when being applied as a chair or seat.

When it is desired to form a table of the aforesigned device, the board 11 is swung upwardly and into a substantially horizon- 110

tal position to overlie the arm rests 2. In this movement, the pins 16 travel in the circular grooves 9 into registration with the downwardly depending grooves 10. The 5 bolts 15 slide within the elongated slots 14 of the arms 13 permitting the arms to move downwardly with the pins 16 traveling within the downwardly depending grooves 10, allowing the board 11 to rest flatly upon 10 the arm rests 2 of the end members 1, thus providing a very efficient table whereby the board 11 will be prevented from swinging out of the horizontal position, owing to the pins 16 occupying the position within the 15 grooves 10.

When it is desired to form a seat of the aforescribed device, the board 11 is raised upwardly and swung to a substantially vertical position, the pins 16 passing out of the 20 grooves 10 into the circular grooves 9. The board 11 then being supported in such a position that the same will rest flatly against the arm rests of the substantially U-shaped members 1, forming an inclined back rest to 25 the seat.

If desired, the bolts 15 may be substituted by set screws 20 as shown in Fig. 7, whereby the adjustment of the arms 13 with relation to the members 1 may be readily regulated by increasing and decreasing the tension of the set screws 20 upon the arms and within the elongated slots 14. The set screws 20 being threaded into the openings of the vertical reinforcing members 7.

It will also be noted that a device has been provided wherein the board 11 may be

swung upon either side of the substantially U-shaped members 1 to provide a seat, which will be accessible from either side thereof.

While I have shown and described the 40 preferred embodiment of my invention, it will be understood that minor changes in construction, combination and arrangement of parts may be made without departing from the spirit and scope of the invention 45 as claimed.

Having thus described my invention, I claim:

A combined seat and table comprising substantially U-shaped end supporting members having web portions disposed uppermost to form arm rests, a seat secured to the ends of the arm portions of said substantially U-shaped members, a seat connecting said members, plates carried by the end members and having circular grooves and downwardly depending grooves in communication with the circular grooves, arms slidably and pivotally connected to the end members, a board secured to the arms, and 50 lugs formed upon said arms and adapted to travel in the circular grooves and the downwardly depending grooves to lock the board in a substantially horizontal position to form 55 a table.

In testimony whereof I affix my signature in presence of two witnesses.

HARRY S. AUSTIN.
